UNITED STATES PATENT OFFICE.

BENJAMIN BROIDO, OF NEW YORK, N. Y., ASSIGNOR TO THE SUPERHEATER COMPANY, OF NEW YORK, N. Y.

METHOD FOR HEATING WITH SUPERHEATED STEAM.

Application filed April 13, 1923. Serial No. 631,945.

To all whom it may concern:

Be it known that I, BENJAMIN BROIDO, citizen of the United States, and resident of New York, in the county of New York and 5 State of New York, have invented certain new and useful Improvements in Methods for Heating with Superheated Steam, of which the following is a specification.

This invention relates to apparatus such 10 as kilns for drying lumber, etc., in which the heating medium used is superheated steam. This steam may be of any desired pressure and may come from any desired or convenient source. Thus it may come directly from the superheater of a boiler especially provided for the purpose, it may be steam extracted from an intermediate stage of a high pressure engine or turbine, possessing some degree of superheat and being 15 re-superheated if necessary, or it may be low pressure exhaust steam which has been re-superheated to the degree desired for heating purposes. The object of the invention is to provide apparatus and means for 20 effecting the heating more economically than has been heretofore done and with apparatus which would be less expensive than hitherto used.

The invention is shown by way of illustration in the accompanying single sheet of drawings in which the single figure shows an installation deriving its steam from a boiler. The figure is more or less diagrammatic and is in sectional elevation.

35 The boiler shown comprises a housing 1, water tubes 2, and a steam-and-water drum 3. The type or construction of the boiler plays no part whatever in my invention and in fact, as above mentioned, the steam used 40 in my invention may be derived from some other source. It is, therefore, thought unnecessary to illustrate the boiler in any greater detail.

The steam is superheated in the superheater 4 and from there is carried by pipe 5, main 6, and pipe 7 to the heating coil or radiator 8 located in the kiln 9. The radiator 8 comprises headers 10 and 11 to which serpentine or coils of other shape are 50 secured. It will be understood that the number, shape and length of these coils is a matter dependent upon conditions such as the degree of superheat imparted to the steam, the heat which it is desired to attain 55 in the kiln, etc. An important point as will

appear presently is the question of steam area in the elements of the radiator.

I have observed that even when superheated steam is used in coils such as described the wall temperature of the coiled elements of the radiator is not that of the superheated steam inside of the coils, nor nearly such temperature, but more nearly approximate that of saturated steam of the pressure prevailing on the inside of the coils. 60 The reason for this has heretofore been obscure and it has not been feasible to obtain wall temperatures of the coils higher than those referred to. I have discovered why only such lower temperatures prevail 65 and my present invention provides for a method and an apparatus for obtaining a wall temperature in the proximity of that of the superheated steam.

When steam, even though superheated, is 70 first introduced into cold coils, a certain amount of initial condensation takes place on the interior walls of the coils, and the water of condensation is ordinarily removed by some form of drainage trap; but it is 75 obvious that drainage alone will not remove the thin capillary film of moisture adhering to the inner wall of the coil.

It is an established fact that under certain 80 conditions water will remain as water in the continued presence of superheated steam, and I have ascertained that when superheated steam is stationary or flows at velocities ordinarily employed through a coil such as that described the interior surface of 85 the coil is wet and it is to this circumstance that I ascribe the fact that the wall itself has a temperature only approximating that of saturated steam of the corresponding 90 pressure. My invention contemplates removing all the moisture on the coil walls due to initial condensation, preventing the formation of any further condensation on the walls during the normal operation of the 95 radiator, and getting the superheated steam into direct contact with the wall. I do this by circulating the steam through the coil at a very high velocity, as I have found that when the steam exceeds a certain so-called critical velocity, it re-evaporates any moisture on the interior walls of the coil and maintains them in a dry state as long as this velocity is maintained. It is particularly to be noted in this connection that 100 the test as to whether or not the proper ve- 105

lacity has been attained is not the quality or 5 temperature of the steam emerging from the coil, as superheated steam may be delivered therefrom while the coil walls remain in a wet condition. The true test is the temperature of the coils. As long as the coil remains at or near the temperature of saturated steam at the pressure used, it is evident that the critical velocity has not been attained and 10 the interior walls of the coil are wet; but if the coil is at the temperature approximately that of the superheated steam passing through it, it indicates that the critical velocity has been reached or passed and that the coil 15 walls are in a dry state, permitting direct and intimate contact between the coil and the steam passing therethrough. The convenient way of obtaining such high velocities is by making the coils comparatively 20 small in diameter, keeping the total cross sectional area of all the coils low. It is for this reason that in the illustration the coils are shown rather small. Obviously other ways can be used to impart this desired 25 higher velocity, such as placing a spiral baffle in the tube, or by resorting to forced circulation. The means first mentioned, that is, using small diameter tubes, is to be understood to be only illustrative. 30 With an arrangement such as described the superheated steam remains in intimate contact with the dry coil walls and the heat of superheat is transmitted through the wall under thermodynamically favorable conditions, that is, with the temperature difference 35 between the heating agent and the heat receiving agent high. This results in a more efficient heat transfer and makes it possible to use less heating surface than 40 under conditions as hitherto used.

The actual speed with which the steam must travel through the heating device to carry out my invention is evidently not a fixed one, nor one exceeding a certain mini-

45
mum, but will vary from case to case depending upon the degree of superheat, the temperature outside of the device, and other factors dependent upon the characteristics of the individual installation.

Obviously the invention can be carried out 50 with apparatus varying considerably from that herein described.

What I claim is:

1. The process of heating with steam, comprising superheating the steam and passing 55 it through the heating apparatus at such velocity that the walls of said apparatus in contact with said steam are maintained in a dry state during the normal operation of 60 the process.

2. The process of heating with steam, comprising superheating the steam and passing it through the heating apparatus at such velocity that the capillary film of moisture resulting from the initial condensation on 65 the walls of said apparatus in contact with said steam is removed by evaporation, and said walls are thereafter maintained in a dry state during the normal operation of 70 the process.

3. The process of heating with steam comprising the steps of taking steam from a source of supply, superheating it and abstracting from it a portion of its heat of superheat under such conditions that it does 75 not come into contact with moist surfaces during normal operation of the process.

4. The process of heating with steam comprising the steps of taking steam from a source of supply, superheating it and abstracting from it a portion of its heat of superheat under such conditions that the temperature of the surfaces to which it gives up heat during normal operation is maintained at substantially the temperature 80 of the superheated steam. 85

BENJAMIN BRODO.
